UNITED STATES PATENT OFFICE.

HENRY A. CARPENTER, OF SEWICKLEY, PENNSYLVANIA, ASSIGNOR TO RITER-CONLEY MANUFACTURING COMPANY, OF PITTSBURGH, PENNSYLVANIA, A CORPORATION OF NEW JERSEY.

RETORT-FURNACE CONSTRUCTION.

1,150,809.

Specification of Letters Patent.

Patented Aug. 17, 1915.

Application filed April 7, 1914. Serial No. 830,162.

To all whom it may concern:

Be it known that I, HENRY A. CARPENTER, a citizen of the United States, residing at Sewickley, in the county of Allegheny and State of Pennsylvania, have invented certain new and useful Improvements in Retort-Furnace Construction, of which the following is a specification.

The present invention relates to new and improved retort furnaces, and more particularly to a type of retort furnace shown in two pending applications for patents filed by me July 3, 1913, Serial #777,215 and Serial #777,216.

In the accompanying drawings, which illustrate an embodiment of my invention as applied to gas retort furnaces or benches, Figure 1 is a part elevational and a part vertical sectional view of a portion of a stack or battery of gas retort benches constructed in accordance with my invention. Fig. 2 is a vertical sectional view of a portion of the stack or battery of gas retort benches shown in Fig. 1 taken on a line extending through one of the flues; and Fig. 3 is a fragmentary view in perspective of a portion of a retort illustrating forms of blocks and the manner of assembling them to form retorts and cross walls.

In most modern retort furnaces of this class, it is customary to build a number of benches arranged side by side, the whole number constituting a stack of benches. In connection with each bench of the stack, means are provided for generating producer gas, and introducing this producer gas, together with secondary air, to a combustion chamber of the bench from which products of combustion are passed around the retorts therein.

In the drawings I have shown a complete bench 1 and portions only of two adjacent benches 2 and 3 of similar construction. As all of the benches are of substantially the same construction, I have deemed it unnecessary to show more than one bench, and the following description will be limited to a single bench of the stack.

As illustrated, the bench is supported upon walls 4 and intermediate blocks or settings 5, the latter forming an arch structure being located intermediate of the lower portion of the bench proper and the recuperators, not shown, but which in practice are located between the walls 4.

6 designates a portion of the combustion chamber which extends longitudinally throughout the length of the bench and is in communication with the bench proper by means of flues through which products 60 of combustion from the combustion chamber are passed, and circulate through flues formed by the cross walls of the bench construction. The producer gas and the secondary air above referred to are both 65 designed to be introduced to the combustion chamber 6 in the usual or any preferred manner.

As illustrated, the bench is constructed of blocks or settings 7 and 8 of appropriate 70 shapes and sizes; and, as preferred, these blocks are respectively provided with flanges 9 and 10 of such a character that when fitted together, they will form two rows of superposed retorts 11 and 12.

13 designates divisional walls dividing the stacks of benches into separate benches.

In the operation of benches of this character as heretofore constructed, some trouble has been encountered due to the influence of 80 heat on the refractory blocks or settings of which the several benches are constructed, and one of the main objects of the present invention is to provide means for effectively taking care of the expansion and contraction 85 of the refractory materials entering into the construction, and particularly the horizontal movement of the blocks as distinguished from the vertical movement, although provision is also made for any vertical movement 90 of the structure due to the expansion and contraction.

To accomplish the end sought, I build 95 each superposed row of retorts of a bench and the cross walls forming the flues surrounding the retorts of blocks or settings of appropriate form, and space the said blocks or settings forming one row of retorts apart from the blocks or settings entering into the formation of the adjacent row of superposed retorts and the flues surrounding said retorts, thereby providing spaces 14 between the adjacent edges of the blocks entering 100 into the formation of the two adjacent rows of retorts and their flues.

The spaces extending along the top of the bench are covered by means of blocks 15, said blocks 15 being secured to and movable with the settings forming one row of retorts and being slidable upon the other set- 105

tings. 16 designates coverings of the spaces at the front of the bench.

In practice, I preferably employ refractory blocks or settings made of practically pure silica, and in the use of this material, it is necessary to provide for the expansion that will occur in bringing the blocks up to the final working temperature. Heretofore, to compensate for the expansion, fillers of 10 various materials, such for example as paste-board and a low grade of fire clay, have been placed between the blocks. In practice, however, these fillers or spacing means have not worked out satisfactorily.

15 The present invention contemplates doing away with the employment of fillers interposed between the adjacent faces of the blocks for the purpose of taking care of expansion. In place of the fillers or spacers, 20 I employ a thin coating of adhesive material, not as a means for spacing the blocks, but solely for the purpose of binding the blocks or setting constituting one row of retorts firmly together, making the blocks 25 or settings constituting the row practically a unit mass. The binding material employed is of such a character that it possesses proper cohesive strength, and which upon vitrifying becomes practically the 30 same as the blocks. This coating material is applied to the adjacent faces of the blocks or settings, and in the drawings I have shown the same designated in black lines 17.

What I claim is:—

35 1. In a retort structure, blocks or settings of appropriate shapes fitted together to form a row of retorts, and blocks or settings of appropriate shapes fitted together to form an adjacent row of retorts, said 40 blocks or settings entering into the formation of the second row of retorts spaced apart from the blocks or settings forming the first row of retorts.

45 2. In a retort structure, blocks or settings of appropriate shapes fitted together to form a vertical row of retorts, and blocks or settings of appropriate shapes fitted together to form an adjacent vertical row of retorts, said blocks or settings entering into 50 the formation of the second row of retorts spaced apart from the blocks or settings forming the adjacent row of retorts.

55 3. In a retort structure, blocks or settings of appropriate shapes fitted together to form a row of retorts and flues for products of combustion, and blocks or settings of appropriate shapes fitted together to form flues for the products of combustion and an adjacent row of retorts, said latter blocks 60 or settings spaced apart from the first mentioned blocks or settings.

4. In a retort structure, a plurality of vertical rows of retorts, blocks or settings of appropriate shapes fitted together to form 75 one row of retorts, and blocks or settings

of appropriate shapes fitted together to form an adjacent row of retorts, said first mentioned blocks or settings being spaced apart from the second mentioned blocks or settings.

5. In a gas retort bench structure, a plurality of vertical rows of retorts, flues for products of combustion, blocks or settings of appropriate shapes fitted together to form one row of vertical retorts and flues, and 75 blocks or settings of appropriate shapes fitted together to form an adjacent row of retorts and flues, said second blocks or settings spaced apart from the first blocks or settings.

6. In a retort structure, cross walls composed of blocks or settings of appropriate shapes fitted together and formed to provide a row of superposed retorts, and a second series of blocks or settings of appropriate shapes fitted together and formed to provide an adjacent row of superposed retorts, 85 said second series of blocks or settings spaced apart from the first mentioned blocks or settings.

7. In a retort structure, blocks or settings of appropriate shapes fitted and bound together to form a row of retorts, and blocks or settings of appropriate shapes fitted and bound together to form an adjacent row of retorts, said blocks or settings entering into the formation of the second row of retorts spaced apart from the blocks or settings forming the first row of retorts.

8. In a retort structure, blocks or settings of appropriate shapes having their adjacent faces provided with an adhesive coating, said blocks or settings fitted and bound together to form a row of retorts, and blocks or settings of appropriate shapes having 105 their adjacent faces provided with an adhesive coating, said latter blocks fitted and bound together to form an adjacent row of retorts, said blocks or settings entering into the formation of the second row of retorts 110 spaced apart from the blocks or settings forming the first row of retorts.

9. In a structure of the character described, a pair of sections each comprising expandable blocks or settings fitted together, the blocks or settings constituting one section being spaced apart on predetermined lines from the blocks forming the adjacent section to provide a space therebetween for lateral expansion of the sections as units. 115

10. In retort structures, a bench of vertical rows of retorts and their settings, said bench having expansion spaces extending vertically and from front to rear of the bench on predetermined lines, said spaces 125 being of widths adapted to compensate for the lateral expansion produced in bringing the bench to its working temperature.

11. In retort structures, a bench of vertical rows of retorts and their settings, said 130

- bench having expansion spaces extending vertically and from front to rear of the bench on predetermined lines, said spaces being of widths adapted to compensate for the lateral expansion produced in bringing the bench to its working temperature, and arch structures for supporting the bench of retorts, said arch structures having similar expansion spaces. 5
10. 12. In gas retort structures, a bench of vertical rows of retorts comprising assemblages of blocks or settings of appropriate shapes, each assemblage providing a complete vertical row of retorts and their settings, the assemblages combinedly providing flues for the circulation of products of combustion, said bench having expansion spaces extending vertically and from front to rear of the bench on predetermined lines, said 15 spaces being of widths adapted to compensate for the expansion produced in bringing the bench to its working temperature. 20
13. In gas retort structures, a bench of vertical rows of retorts comprising assemblages of blocks or settings of appropriate shapes, each assemblage providing a complete vertical row of retorts and their settings, the assemblages combinedly providing flues for the circulation of products of combustion, said bench having expansion spaces extending vertically and from front to rear of the bench on predetermined lines, said 25 spaces being of widths adapted to compensate for the expansion produced in bringing the bench to its working temperature. 30
- bringing the bench to its working temperature, one of said spaces being positioned between the opposing faces of the assemblages. 35
14. In gas retort structures, a bench of vertical rows of retorts comprising assemblages of blocks or settings of appropriate shapes, each assemblage providing a complete vertical row of retorts and their settings, the assemblages combinedly providing flues for the circulation of products of combustion, said bench having expansion spaces 40 extending vertically and from front to rear of the bench on predetermined lines, said spaces being of widths adapted to compensate for the expansion produced in bringing the bench to its working temperature, arch 45 structures for supporting said assemblages, opposing ends of such arch structures being spaced for similar expansion purposes. 50
15. In gas generating apparatus, a refractory mass structure forming a plurality of benches and adapted to be subjected to high temperatures, said benches being subject to lateral expansion in reaching the desired temperature, and means within the planes of the structure to accommodate for individual 55 expansion of benches lengthwise of the structure. 60

In testimony whereof I affix my signature in presence of two witnesses.

HENRY A. CARPENTER.
